UNITED STATES PATENT OFFICE.

ALBERT McDOWELL, OF NEW YORK, N. Y.

ADJUSTABLE PATTERN FOR DRAFTING DRESSES.

SPECIFICATION forming part of Letters Patent No. 310,297, dated January 6, 1885.

Application filed December 11, 1883. (No model.)

To all whom it may concern:

Be it known that I, ALBERT McDOWELL, of the city and county of New York, in the State of New York, have invented certain new and useful Improvements in Adjustable Patterns for Drafting Dresses; and I do hereby declare that the following is a full and exact description thereof.

It has been found expedient to aid the determining of the proper contour of the several parts of a garment, more especially the upper portion of ladies' dresses, by employing adjustable patterns for the several parts—front, sides, and back—each with their several dimensions variously adjusted. I have invented improvements therein whereby I am able to determine the sewing-line and also the cutting-line directly from the outer and inner edges of proper border-pieces, can allow for variations in the curvature of the back by drawing a line from an offset on the inner edge of such pattern, determine the line for the buttons and button-holes in the center of the front, and also the line of fold and of the cutting-edge of the front, support the upper edge of proper changeable dart shapers or gages by a single piece of the frame extended from the front gage to a slot in the bust-gage, adjust and secure the dart-gages by a single slot in the waist-gage, draft the hip-darts with any amount of breadth at the top as well as at the bottom, indicate directly the width of the hip-dart by graduations on movable pieces connected, vary the width of the darts at will without changing the waist-measure, vary the width of the front across the bust and the space under the arm and the under arm-piece each independently, change the width of the back at the waist at will, change the dimensions and inclination of the armhole-gage, change the dimensions of the neck and the dimensions and inclination of the shoulder-gages, and indicate a properly-swelled extension downward for the skirt of the basque at the back and sides. The operator takes the dimensions with a tape measure of the different parts of the body as follows: around the neck, across the back, the length of back, length under the arm, length of front, armhole, bust-measure, height of darts, waist-measure, and the hip-measure

about six inches below the waist, and size of the hip-dart. Having these measures, the operator sets the several parts of the pattern each to its several measures, and, laying them flat upon the material, marks with a pencil or chalk along the proper edges and produces the draft adapted to fit the form exactly without necessity for the ordinary tedious "fitting." I have in my experiments made the patterns of sheet-brass of sufficient thickness to properly support itself; but various other materials may be used, if preferred.

The accompanying drawings form a part of this specification, and represent what I consider the best means of carrying out the invention.

Figure 1 represents the pattern for the front body; Fig. 2, the pattern for the back body, and Fig. 3 the pattern for the side body. All these are face views with the parts adjusted to correspond each with the other. Each represents one half, and serves, by being applied on folded material, to determine the outline of two corresponding pieces of fabric. Fig. 1 represents the cut fabric to constitute half of the front of the dress as shaped by the aid of the pattern Fig. 1. Fig. 2 shows the cut fabric to constitute half of the back of the dress as shaped by the aid of the pattern Fig. 2. Fig. 3 represents the cut fabric to constitute half of the side body of the dress as shaped by the aid of the pattern Fig. 3. Figs. 4 and 5 represent the dress-body made up. Fig. 4 is a front view, and Fig. 5 a back view.

I will use the single word "connected" to imply that parts are adjustably secured together with liberty to slide one upon another by means of suitable slots, and a rivet or screw or clamp without liberty to turn relatively each other.

Referring to Fig. 1, the plates A and B' are connected. The plate B' is of branched form and connected to the plates B' and B'. The plate C' is hinged to the plate B' and connected to the plate C'. The plate C' is adjustably hinged to the plate D', which is connected to the plate D'', which in turn is hinged to the plate E, which latter is connected to the horizontal extension or branch B''' of the branch plate B''. The plate G' is connected to the

plate C^2 , which latter is hinged to the slightly curved plate H' , which in turn is connected by a straight slot and guides to a reversely curved plate, H^2 , which is hinged to the upper end of the plate A , thus completing the contour of the pattern for the front of the dress. The curved parts H' and H^2 serve for drafting the shoulder. They are just of the width required for the seam, and give the curves required. Other important portions of the pattern, as D' D^2 , are similarly conditioned with regard to width and proper curves. The operator, when the adjustable pattern is in position on the fabric, draws with a pencil or chalk on the inner edges of these parts to lay out the sewing-line, or the line along which the fabric should be joined to the next piece, and draws with the same or a different color along the outer edge of the pattern to mark the line where the material should be cut. The curvatures of these parts of the pattern are so adjusted that the curves will flow smoothly into each other whether the parts be extended more or less, thus allowing a wide range of adjustment while maintaining the proper graceful curves. These ends are attained by straight slots and a straight movement of the parts relatively to each other in opening or closing. At the front edge the several plates B^2 B^3 are slotted and equipped with suitable rivets and screws, to serve as guiding and adjusting means. The slots 1 extend along the line which makes the true center of the front of the dress. Marking with a pencil through these slots denotes the line on which the buttons and button-holes shall be located. The material of the several plates is extended continuously beyond this line to the proper distance, a half-inch, more or less, to denote the line to fold the fabric. This line may be only marked on the fabric by tracing with a pencil along the edge 2 thus presented. A large rectangular opening separates this edge in a sufficiently wide margin held farther back. By marking along the extreme outer edge, 3, the line of cutting is indicated. The material from the folding edge to the cutting edge is to be turned under the dress at the time to form the usual re-enforcing or strengthening of this portion for the buttons and button-holes.

is a single narrow plate, secured at one end by a screw, f , adjustable in a vertical slot in the piece B^2 , and at the other end by a pin rivet, f' , free to slide in the plate E . This plate F has a single slot extending longitudinally, receiving screws z^2 z^6 , one of which is the pivot for the pair of connected plates Z^2 Z^2 , and also for the counterpart thereof, Z^1 Z^1 . These two pairs of connected plates form the outlines or gages for one of the darts. The other screw, z^6 , forms a corresponding pivot for two corresponding pairs of connected plates, Z^5 Z^6 , Z^7 Z^8 , which are the guides for drawing the next dart. The lower end of the plate Z^1 is hinged to

at z' . The lower ends of the plates Z^2 Z^5 are united together and to the plate C' by a single screw, z^1 . Another screw, z^1 , performs the functions of uniting the plates Z^7 and C^2 , and also aiding to connect the plate C^2 with the plate C' . I will mark the word "dart" in the spaces in the pattern which correspond to the darts. By slackening the several screws the inclinations of the darts may be varied by moving the upper screws, z^2 z^6 , to the right or left. The lower end of the first dart may be narrowed or widened by shifting the screw z^2 to the left or right, and by moving the screws z^2 and z^6 to the left as far as they will go the front dart can be dispensed with entirely when desired. The lower end of the second dart may be narrowed or widened by shifting the screw z^6 to the left or right. This movement will correspondingly carry the plate C^2 to the right or left, and thus avoid disturbing the size of the waist, whether one or two darts are used or whether they are large or small. The connected pair of plates Z^9 Z^{10} serves to mark one side, and the connected pair of plates Z^{11} Z^{12} the other side, of a piece which is to be cut or stitched out under the arm, and which I will term the "third" or "hip" dart. The space representing this dart is indicated by the words "hip-dart." These dart-gages extend a little below the waist-gage. Their inner edges are curved toward each other near the bottom. By following the line thus indicated, the hip-dart is extended downward into the material below the waist, and by coming rapidly to a point, or as near together as desired, gives the required fullness for the hip. I have not deemed it necessary to extend any of the other gages downward in this portion of the apparatus. At the sides and back I have provided liberally for producing the exact form of the narrow skirt, which I will term the "basque" skirt, as will appear further on. The upper ends of the hip-dart gages Z^9 Z^{10} Z^{11} Z^{12} are adjusted in a horizontal slot in the plate E by screws z^{10} z^{12} . The lower portions of these hip-dart gages are adjustable in various positions on the plate C^2 by a single screw, z^{11} , connected to the plate Z^{11} . A narrow slotted movable plate, I , lies on the front of the plate C^2 , and enables this screw z^{11} to also control the position of the lower end of the other hip-dart gage, Z^9 Z^{10} , by means of a rivet, z^9 . A closely-corresponding narrow plate, J , lying in front of the plate E , receives both screws z^{10} z^{11} . It is changeable to the right and left with each change of position of the upper end of the plate Z^{10} . These plates I and J are each graduated on their faces and serve to indicate to the eye by inspection the distance apart at which the hip-dart gages Z^9 Z^{10} and Z^{11} Z^{12} are set, and consequently the width of the hip-dart at the top and bottom, respectively. The connected plates D' and D^2 constitute the gage for the up and down seam which joins the front to the side of the dress. They are adjusted to the right and left at the bottom by the screw d' , which en-

gages in a long horizontal slot in C^2 . The upper end of this gage is adjusted to the right and left by the screw d^2 , which is inserted through a long slot in the plate E . The upper ends of the hip-dart gages $Z^{10} Z^{12}$ are extended a little above the plate E to allow the marking of the width of the hip-dart at that point precisely.

The curved plate G' , with its connected plate G^2 , performs important functions. The two constitute a gage for the armhole. Its lower end is held by the screw z^{10} , which is also the pivot for the upper end of the hip-dart plate Z^{10} . It may be practicable to so narrow and curve these plates $G' G^2$ that the inner edge may serve to indicate the sewing-line; but I have represented them with the lower end of G' wider, and I prefer to so construct it, leaving it to the judgment of the operator to draw the lower portion of the sewing-line at this point.

Referring to Fig. 2, M' is an upright plate. (Shown as composed of two or more pieces, but riveted rigidly together, so as to serve as one plate, and it will be so described.) The lower portion is slightly inclined, and is considerably wider, so that while the outer edges connect directly, the inner edges of the upper and lower portions, respectively, form a considerable offset at y . A branch, M^{*2} , extends out laterally, and is provided with a horizontal slot. This plate M' is connected to a vertical plate, M^2 , having a rigid lateral branch, M^{**2} , at right angles. The upper portion of M^2 is connected to a plate, M^3 , having a curved slotted branch, M^{***2} . The three plates $M' M^2 M^3$ form the gage for the center of the back. The curved branch M^{***2} serves as the gage for the neck.

N' is a slightly-curved plate having a screw, n' , by which its upper end is adjusted at any desired point in the slot in M^{***2} . To N' is connected a slightly-curved plate, N^2 . These plates $N' N^2$ constitute the gage for the shoulder of the back. In use, this gage is set a very little longer than the corresponding gage, $H' H^2$, for the shoulder of the front, in order to insure that when the parts are properly united the fabric in the front shall be held smoothly extended. It will be observed that the slight curvatures of these plates $N' N^2$, as also of the corresponding plates, $H' H^2$, flow into each other and produce the required reversely-curved seam to give a graceful contour to the shoulder of the dress in all conditions of extension, although the slots are straight.

O is a curved plate hinged to the lower extremity of N^2 . It alone constitutes the arm-hole-gage for the back. A plate, m , is connected to the horizontal arm M^{**2} . These parts M^{**2} and m are set by the screw m^* with the desired amount of extension and determine the width of the back. A screw, p' , attaches the plate m to any desired point in the slot in O . The same screw, p' , serves as a pivot

for the upper end of a curved plate, P' , which connects to a correspondingly-curved plate P^2 , which is provided with a screw, p^2 , adjustable in the slot in the branch M^{*2} .

P^3 is a slightly-curved plate hinged to the same screw p^2 . Its lower end is secured by screw, p^3 , which is adjustable in the slot in horizontal plate, Q , which is hinged to the lower end of M' . With this pattern, as with the front pattern previously described, when the several parts are adjusted according to the measures taken, the pattern is laid on the cloth, and a mark drawn along the outer edge denotes the cutting-line. A mark drawn along the inner edge gives the sewing-line.

There is one point of importance when something is left to the unaided judgment of the operator. A line drawn along the inner face of the lower part of the plate M' gives the sewing-line for the back of the skirt. From the point y an inclined line, $y y'$, is drawn, joining the inner edge of the plate M' at a higher or lower point, according to the form of the person being fitted. It should join at the point where the back is the fullest. This inclined line $y y'$, the inner edge of the lower part of M' , and the inner edge of the upper portion of M^2 and of M^3 form the sewing-line for the back seam. It will be observed that the branch M^{*2} corresponds with the waist of the dress, and that the plate Q corresponds with the bottom of the skirt.

Referring to Fig. 3, T' is a plate having an inclined branch, T^* , at the upper end. It is connected to the plate T^2 . These plates are curved but connected by straight slots. To the lower end of T^2 is hinged a curved plate, U , to the lower end of which latter is hinged a straight plate, V , having a long slot in which is pivoted, by an adjustable screw, v , a plate, W' , and connected to a curved plate, W^2 , which is hinged to the branch T^* at the top. A plate, X , hinged to the lower end of T^2 , is provided with a long slot in which is set a screw, x , attached to the plate W' . This pattern shapes the side body of the dress. A line is drawn with a pencil or chalk along the outer edges of the several plates to indicate the cutting-line. Another line drawn on the inner edges of the several plates indicates the sewing-line. The plate X corresponds to the waist-line. The plate V corresponds to the lower edge of the skirt. The branch T^* at the top drafts the portion of the side body which is presented under the arm.

Modifications may be made in some of the details. I prefer to use hard brass, but believe that steel and various other materials may be used for the several plates and fastenings, care being taken to avoid oxidation. I can employ thin wood made of veneers glued crosswise to prevent splitting.

The construction of the rivets, screws, or their equivalents, including various forms of clamps, which gage and confine the several connected parts, may be varied. I deem it im-

rtant that these parts be arranged to allow easy adjustment of length and to give the proper stiffness. The width of the slots in the several parts may be varied. By clamping around the parts the slots may be dispensed with, and by making the clamps short they will not fatally interfere with the use of the outer and inner edges as guides for drafting several lines. The gage $M^{**} m$ may be made to serve in one piece by giving surplus length and making the connection at either end or both ends adjustable. So, also, variations of other gages, including the side-seam gage, D^2 , and the several hip-dart gages, may be made in a single piece with a surplus of length, and allowed to project beyond the extent required at one or both ends. The projecting lower ends of the hip-dart plates $Z^1 Z^2$ may be omitted, and all of the hip-dart below the waist may be drawn by the operator without aid from the gages; or, if preferred, there may be a further extension downward of these parts, or of additional parts applied for the purpose. I can equip the whole front pattern with parts intended to aid in drafting the skirt at the front; but I do not deem such necessary or desirable.

Some of the advantages due to certain features of the invention may be separately enumerated as follows: First, by reason of the fact that the border is of a width corresponding to that required in the fabric for the seam or portion outside of the sewing-line, I am able to draft the sewing-line and the cutting-line by a single application of the pattern; second, by reason of the fact that the front gage, $B^1 B^2 B^3$, is formed with the slots 1 and the two parallel edges 2 and 3 at the proper distances therefrom, I am able, by a single pattern and at one application thereof, to draft the center line for the buttons and button-holes, and also the folding-line and cutting-line; third, by reason of the fact that the dart-brace plate F , slotted as shown, and receiving the screws z^1 and z^2 , to allow the adjustment of the dart-gages, is adjustable in a vertical slot in the front plate, B^2 , while the other end is allowed to play freely in the horizontal slot in the plate E , I am able to employ a brace in a single piece and to adjust its front at any height, and to insure that the necessary adjustment of the other end is automatically made; fourth, by reason of the connected plates C^1 and C^2 , in combination with each other and with the front-line gage, $B^1 B^2$, and with two or more dart-gages, $Z^1 Z^2 Z^3 Z^4$, I am able to vary the width of the dart or darts without changing the waist-measure; fifth, by reason of the branch B^{**} from the central front plate, B^2 , and the adjustably-connected plate E with the side-seam gage $D^1 D^2$, hip-dart gage $Z^1 Z^2$, armhole-gage G' , and adjusting means $z^1 z^2$, I am able to change the size of the armhole, the width of the front and the top of the under arm-piece, and to place the under arm-piece and front any distance apart with-

out losing the bust-measure; or, I can make these variations as required without varying the bust-measure; sixth, by reason of the independent screw z^1 connecting the plate Z^2 to the plate E at any required distance from the screw z^1 , I am able to set the width of the upper end of the hip-dart, then to shift the same to right or left, and thus to draft the under arm-piece in any desired position relatively to the grain of the cloth; seventh, by reason of the combination, with the plates C^2 and E , of the plates I and J , slotted and graduated as shown, each pivoted at one end to one of the hip-dart gages and adjustable relatively to the other hip-dart gage, I am able to ascertain by inspection the width of the hip-dart at the top and bottom, respectively, and thus to avoid the necessity for any measuring or calculating in order to determine how much to allow therefor in the waist-measure or bust-measure; eighth, by reason of the branch M^* extending horizontally from the back gage, slotted as shown, the screw p^2 , adjustable therein, and adjustable gage $P^1 P^2$ for the curved line, I am able to draft the back with any width at the waist, according to the fashion, and by graduating the slot on the branch M^* may determine instantly by inspection the amount to be deducted therefor from the waist-measure on the side body; ninth, by reason of the extension of the plate W' below the waist-line, and of the hinge-plates V and U , in combination with the plate for drafting the parts immediately above, I am able to draft the side of the skirt at the same time and with a certainty of harmony with the side body.

I claim as my invention—

1. An adjustable pattern for drafting garments, having the whole or a portion of the edge formed of plates of such width and so arranged that the inner edge corresponds to the sewing-line and the outer edge to the cutting-line, so that both lines can be drafted therefrom at one operation, all substantially as herein specified.

2. In an adjustable pattern for drafting the front of a garment, the front gage composed of two or more separate plates, connected as shown, and provided with longitudinal slots 1, corresponding to the line of buttons and button-holes, an edge, 2, corresponding to the folding-line, and an edge, 3, corresponding to the cutting-line, combined and arranged so that all three lines may be drafted at a single application of the pattern, all substantially as herein specified.

3. In an adjustable pattern for drafting the front of a lady's garment, two or more dart-gages having their lower ends supported in the waist-gage at adjustable distances apart, in combination with a single brace, F , pivoted at adjustable heights in the front gage, B^2 , while the other end is free to adjust itself on the bust-gage E , as herein specified.

4. In an adjustable pattern for drafting the front of a lady's garment, the extensible plates

C' C^2 , in combination with each other, and with a suitable front-line gage and two or more extensible dart gages, Z' Z^2 Z' Z^8 , and pivot-pins z' , z^2 , z^6 , and z^7 , as herein specified.

5. In an adjustable pattern for drafting the front of a lady's garment, the horizontal plate E , in combination with the branch B^{**} of the front plate, B^2 , provided with suitable guiding and adjusting means, the adjusting-screw z^{10} , connecting the armhole-gage G' at a changeable point, and the hip-dart gages Z^{10} Z^{12} , and side-seam gage D' D^2 , and provision for adjusting their positions, all adapted to serve as herein specified.

15. 6. In an adjustable pattern for drafting garments, the independent connections z^{10} z^{12} on the bust-gage E , whereby the hip-dart gages Z^9 Z^{10} Z^{11} Z^{12} are adjustable at variable distances apart at top, in combination with means for also adjusting the distance apart at the bottom, and for shifting the position of the piece relatively to the grain of the cloth, substantially as and for the purposes herein specified.

25. 7. In an adjustable pattern for drafting garments, the graduated plates I and J , in com-

bination with the hip-dart gages Z^9 Z^{10} and Z^{11} Z^{12} , and with the properly slotted gages C^2 and E , arranged to serve as herein specified.

8. In an adjustable pattern for drafting the back of a garment, the upright plate M' , branch or cross piece M^* , and curved gage P' P^2 , pivoted at each end and made in two separate parts, extensible as shown, in combination with the adjusting means p^2 , adapted to serve as herein specified.

9. In an adjustable pattern for drafting the side body of a garment independent of the back and front, the plates U V W' , hinged and adjustable, as shown, in combination with each other and with the plates T' T^* W^2 , for drafting the side body, substantially as herein specified.

In testimony whereof I have hereunto set my hand, at New York city, New York, this 7th day of December, 1883, in the presence of two subscribing witnesses.

ALBERT McDOWELL.
